UNITED STATES PATENT OFFICE.

HARRY S. HART, OF CHICAGO, ILLINOIS, ASSIGNOR TO NATIONAL DUMP CAR COMPANY, OF CHICAGO, ILLINOIS, A CORPORATION OF MAINE.

DUMP-CAR-DOOR LATCH.

Application filed May 6, 1922. Serial No. 558,980.

To all whom it may concern:

Be it known that I, HARRY S. HART, a citizen of the United States, residing at Chicago, in the county of Cook and State 5 of Illinois, have invented certain new and useful Improvements in Dump-Car-Door Latches, of which the following is a specification.

This invention relates to means for controlling the latching and unlatching of dump car doors, and particularly to the type of controlling mechanism disclosed in my application Serial No. 526,588, filed January 3, 1922, wherein I have described and 10 claimed latching mechanism comprising latches and a toggle lever connected with the latches and moved into and out of locking position by the latching and unlatching movements; also means whereby the toggle lever can be positively moved to unlatch 15 the door from a vantage point which does not involve the presence of the operator in the path of the discharging cargo.

One object of the present invention is to 20 provide an improved means through which to impart the unlocking movement to the toggle lever in an arrangement such as that described in my aforesaid application; also to adapt said means to impart locking movement as well as unlocking movement. Accordingly, one feature of the present invention consists in providing the toggle lever with a toggle actuating arm fulcrumed upon and in pivotal relation to a latch but angularly rigid with relation to one member 25 of the toggle lever, so that it can impart locking and unlocking movements to the latter; and extending to within reach of an operator occupying the vantage point referred to; the said toggle actuating arm, in the preferred embodiment of the invention, constituting a continuation of or existing for a part of its length in common with the toggle member to which it is immediately related, and which is fulcrumed on a latch. In other words, one of the members of the toggle lever is made of such length that it can be hinged to the other member thereof at such a point intermediate of its ends as to provide a toggle actuating arm extending to the aforesaid vantage point for operation; and said arm lends its leverage in controlling the toggle

in locking as well as unlocking movements, and at all times adds to the safety of the 55 device by exerting its weight in the direction to hold the toggle locked.

Another object of the present invention is to utilize the toggle actuating arm for locking the toggle against unlatching movement, and, to this end, a further feature of the invention consists in so constructing and locating the toggle actuating arm that its free end can be forced into engagement with a keeper when the toggle is in locking 60 position, the keeper being of such construction that it holds the arm in such engagement until the arm is intentionally released therefrom; the preferred embodiment of 65 this feature of the invention also involving 70 the utilization of inherent resiliency in the arm to return its free end, when so released, to a path which is free from obstruction by the keeper.

In order that the invention may be fully 75 understood, the preferred embodiment thereof will be described in connection with the accompanying drawing, in which—

Figure 1 is a side elevation of a portion 80 of a freight car and its drop door and latching mechanism, with the present invention embodied therein.

Figure 2 is a detail view of the latching mechanism of Figure 1 shown on an enlarged scale, and with unlock-positions of 85 the parts indicated in dotted lines; and

Figure 3 is a top plan view of the parts shown in Figure 2.

The embodiment of the invention herein selected for illustration comprises in general the illustrative embodiment of my previous application herein identified, with the present improvements added thereto. Thus, 90 5 represents a portion of a dump car body, 6 the dump doorway thereof, and 7 the 95 door for closing said doorway. Door 7, being suitably hinged, is retained in closed position by the engagement of its cleats 9, by latches 10 pivoted at 11 to the outer side wall of the car in position to engage beneath said cleats when the door is closed. Toggle arms 12 hinged together at 13 are 100 pivotally connected to the latches at points 14 which are remote from the latch pivots 11 so that the toggle arms partake of the 105 movements of the latches; means such as

the limiting lug 15 being provided on one toggle arm in position to engage the other toggle arm and prevent the downward breaking of the toggle lever; stops such as 16 being provided on the respective latches to limit the unlatching movement of each so that the one which reaches its limit of movement first will constitute a point of anchorage to insure completion of movement of the other; and dogs 19, pivoted at 20, and carrying limiting stops 22, being so arranged in the paths of the cleats 9 that they are held elevated so long as the door is closed, but gravitate into the paths of the toes 21 of the latches when the latter are withdrawn and the door drops, and thus detain the latches and toggle lever in unlock-position until the door is thrown shut and cleats 9 again displace the dogs upward.

In the construction constituting the basis of my previous application aforesaid, one of the toggle arms was constructed with lugs to receive a lever through which to displace the toggle from locking position, but this lever, being removable, was subject to loss, thus inviting impairment of the toggle lever through hammering and other improper attack; the lever could not act to assist in rendering the lock more secure; it was not related to the toggle member in the most efficient position; and it did not insure the full measure of safety in the position occupied by the operative in manipulating the lever. The present invention avoids these several disadvantages, including tendency toward rough usage of the toggle lever which is the underlying element of safety in the locking of the door, by providing a permanently related operating arm for moving the toggle lever to unlocking position, and relates this arm in a manner to enable it to not only serve more advantageously but perform additional functions. Accordingly, the present invention consists in mounting, in substantially rigid angular relation to a member, such as the toggle member 12, in the general organization of parts described, an arm 17 which constitutes an extension of the toggle member beyond the point 13 at which it hinges with the other member; and extending this arm in position to engage with a keeper 18 when the toggle is in locking position. By disengaging arm 17 from the keeper 18 and raising the arm, toggle lever 12 can be broken upward into unlocking position, where the latches 10 will be arrested by the dogs 19; and when the door has been thrown shut, and dogs 19 have been displaced from the latches 10, so that the latches can engage beneath the cleats 9, the arm may be used to force the toggle all the way downward into firm locking position with greatly augmented pressure, thus overcoming any resistance to complete locking

movement. Keeper 18 will be out of the normal path of arm 17, but the arm will be constructed with inherent resiliency sufficient for deflection of the arm into interlock with the overhanging lip of the keeper, and for springing the arm back to its free path of movement when voluntarily displaced from the keeper.

It will be seen that while in the specific embodiment selected for illustration, the arm 17, constitutes an integral extension of a member of the toggle lever, in the analysis of the organization of parts, said arm constitutes a lever which is fulcrumed upon and partakes of the movements of a latch to and from the door part; it is rigid with a member of the toggle lever so that it transfers its movements to said toggle arm and thereby controls the toggle; it is presented in a relation to add its weight to that of the toggle members in the direction of locking; and it lies in a direction which leaves it unmoved by buffing and pulling shocks imposed upon the car in travel.

I claim:

1. In combination with a dump car door and its latch, a toggle lever pivotally connected with and adapted to impart latching and unlatching movement to said latch, and a toggle actuating arm angularly rigid with a member of the toggle lever.

2. In combination with a dump car door and its latch, a toggle lever pivotally connected with and adapted to impart latching and unlatching movement to said latch, and a toggle actuating arm angularly rigid with a member of the toggle lever; said arm constituting an extension of said member.

3. In combination with a dump car door and its latch, a toggle lever pivotally connected with and adapted to impart latching and unlatching movement to said latch, and a toggle actuating arm angularly rigid with a member of the toggle lever; said arm constituting an extension of said member beyond the hinging point of the toggle lever.

4. In combination with a dump car and its door, latching mechanism comprising latches depending from pivots on the car, a toggle lever pivotally connected with the latches at points remote from their pivots and having a hinging connection intermediate of said latches, and an operating arm extending from a member of said toggle lever in a direction to urge the toggle lever to locking position by the weight of the arm.

5. In combination with a dump car door and its latch, a toggle lever pivotally connected with and adapted to impart latching and unlatching movement to said latch, and a toggle actuating arm angularly rigid with a member of the toggle lever; said arm being adapted to engage a keeper when the toggle lever is in locked position.

6. In combination with a dump car door

and its latch, a toggle lever pivotally connected with and adapted to impart latching and unlatching movement to said latch, and a toggle actuating arm angularly rigid with a member of the toggle lever; said arm being adapted to engage a keeper when the toggle lever is in locked position, located out of the

normal path of the arm, and said arm being displaceable from its path to interlock with said keeper.

10

Signed at Chicago, Illinois, this 1st day of May, 1922.

HARRY S. HART.
